United States Patent Office

Des. 216,268
Patented Dec. 9, 1969

216,268

NAPPY

Ben Seibel, New York, N.Y., assignor to Fostoria Glass
Company, Moundsville, W. Va.

Continuation-in-part of design application Ser. No.
10,438, Feb. 5, 1968. This application Dec. 4, 1968,
Ser. No. 15,032

Term of patent 14 years

Int. Cl. D7—01

U.S. Cl. D36—2

FIG. 1

FIG. 2

FIG. 3

This is a continuation-in-part application of application Ser. No. D. 10,438 filed Feb. 5, 1968, and now abandoned.

I claim:

The ornamental design for a nappy, as shown and described.
